UNITED STATES PATENT OFFICE.

WILLIAM A. LORENZ, OF HARTFORD, CONNECTICUT, ASSIGNOR TO THE OTAKA FABRIC COMPANY, OF HARTFORD, CONNECTICUT, A CORPORATION OF CONNECTICUT.

PAPER CRINKLING.

Application filed December 9, 1920. Serial No. 429,317.

To all whom it may concern:

Be it known that I, WILLIAM A. LORENZ, a citizen of the United States, residing in Hartford, in the county of Hartford and State of Connecticut, have invented certain new and useful Improvements in Paper Crinkling, of which the following is a specification.

This invention relates to gathering paper by forming longitudinal flutings therein, and also to means for transversely crinkling the paper.

Certain features of the apparatus disclosed herein are also disclosed in my co-pending application, Serial No. 346,310, filed December 20, 1919, in which the web of paper is led through devices which flute or corrugate it longitudinally, and is then carried against a doctor-blade which cross-crinkles the corrugated web.

Where the web is very wide, difficulty may in some cases be encountered in gathering it widthwise, since the tendency is to effect a substantial narrowing of the width of the web, due to forming the flutes in the paper, and since this fluting is accompanied by a drawing of the paper laterally through the flute-forming devices between which the web is pulled along. This lateral gathering of the paper engenders friction, which is augmented by the intermeshing arrangement of the gathering devices; the friction increasing with the depth of the corrugations, with consequent liability of weakening and rupture of the web.

To reduce the difficulty from this source to a low or negligible point, the web, according to the preferred manner of practicing the present invention, is first folded longitudinally, thus reducing its width to about one-half of the original width, and then the double-ply web is readily corrugated and crinkled. The invention, however, is not limited to a double-ply web, as the web may, if desired, be fan-folded into a triple ply; or it may be made four ply in some cases. By folding the web, its width is reduced sufficiently to reduce the friction by half or more, and hence to enable it to be drawn into the required lateral gathers with little or no difficulty. Moreover, the resistance of the paper to being ruptured at the lateral gathering operation is doubled, since the friction for the two-ply or other fan-folded web is no greater, as it is being gathered later-

ally through the corrugated intermeshing guides, than would be the case with a single ply; but the doubled plies offer twice the resistance to rupture, liability to which may hence be eliminated.

Preferably the two-ply web is formed by making two longitudinal folds in the original web, so that the edges lie along the central line of the folded web. This folding may be done by a former similar to that usually employed for folding a web preparatory to manufacturing bags therefrom. The edges may meet at the center of the folded web, or they may be made to overlap; but preferably they do not quite meet, a small space being left between them, as illustrated in the drawings.

Another feature of the invention relates to means for improving the quality and appearance of the corrugations in the web. This is done by passing the web between improved corrugating rolls in which the corrugations are formed in wavy lines, so that the corrugations in the finished web are correspondingly wavy. So far as this ornamental effect is concerned, the corrugated web may be regarded as a new article of commerce, whether or not it is also subsequently cross-crinkled. The wavy corrugations may also be produced in single-ply paper when desired.

In said co-pending application, the crinkling is performed by means of a doctor-blade, which has a scalloped edge to fit in the corrugations in the cylinder around which the web is carried, so that the web is crinkled by being crushed against the doctor-blade. According to the present invention, the doctor-blade is caused to reciprocate endwise to and fro across the surface of the corrugating cylinder, so as to accommodate the wavy configuration of the grooves in the surface of the cylinder; the doctor-blade having tongues, scallops or corrugations which fit or project into said grooves. The crinkled paper produced by this method is highly ornamental, and this feature of the invention may apply to single-ply paper as well as to superposed plies or to folded webs.

It will be understood that two or more superposed plies of paper may be delivered from separate supply rolls to the machine, and corrugated simultaneously, and also crinkled, and that the same advantage will be gained as to reduction of liability of rup-

ture at the corrugating operation as is gained in the case of a folded web; while a substantial reduction in cost is effected by operating on several webs at once.

- 5 It will also be understood that after the folded web is corrugated and crimped, it may be opened out to its full width, either before or after it has been severed transversely into sheets; the full-width sheet being substantially the same as it would have been if it had been passed unfolded through a wider machine.

Other features and advantages will hereinafter appear.

- 15 In the accompanying drawings,

Figure 1 is a plan of a machine embodying the present invention in one form.

Figure 2 is a sectional side elevation taken at about the line 2—2 of Figure 1.

- 20 Figure 3 is a plan showing the two-ply web gathered laterally by means of a guide device having sets of converging grooves and bars.

The web 10 is led from a supply roll 11, which is retarded by a weighted friction strap 12. The web passes up over an introductory roll 13, and then downwardly and forwardly beneath a folder comprising an inclined apron portion 14. The sides of the 25 apron converge to constitute a former for the web, whose edges are turned over the apron. There is a horizontal extension at 15 to form a tongue portion which is a continuation of the folder or apron. The folding of the sides of the web over the former is aided by guide-rolls 16, which are arranged at the angle between the apron and the tongue. The apron and tongue are supported by a bracket 17, hung from a cross-bar 18 of the framework. There are also provided guide-fingers 19, beneath which the folding web passes, whereby the web is held down upon the former. Preferably a 30 space 20 is left between the adjacent edges of the folded web. Any other suitable form of folding device may be used, and the web may be otherwise folded into the desired 35 number of plies.

From the former the folded web passes 40 between power-driven pressing and drawing rolls 21 and 22; roll 21 being preferably spring-pressed and adjustable. After leaving these rolls, the paper may pass over a wetting or moistening device, which may 45 be of any suitable form; as for example, a spray pipe 23 directing a jet of water against the upper side of the paper; the jet being confined by a hood 24 provided with a drain pipe 25. The water or steam is supplied through a pipe 26. A duplicate spraying device 24^a, Figure 3, may be provided at a subsequent point, for moistening the top of the two-ply web; and it may resemble the moistening device already described, but inverted.

The paper may then pass under a straining bar 27, and over a roll 28, having corrugations 29 in its periphery, for co-operation with corrugations 30 in a roll 31, to press corrugations into the wet web.

If the paper be not too heavily sized, it will readily absorb water, and be sufficiently dampened and softened to render it slightly stretchable, so that the corrugations may be effectively rolled and pressed therein without rupturing the paper. It will be understood that, if desired, in some cases, the preliminary step may be taken of gathering the web laterally into corrugations or pleats, by means of a converging set of tapering intermeshing bars or fingers, as illustrated at 31^a, Figure 3, and disclosed in said application; whereupon the gathered paper may be presented to rolls, for rolling or pressing the corrugations into the paper. It will be further understood that in either case the extent to which the web must yield, stretch, flow or slip laterally, is reduced one-half because of the folded condition of the web, thereby securing the advantages already explained.

The roll 31 is the main cylinder of the machine, and is provided with a gear 32 in mesh with pinion 33, connected to a pulley 34, over which runs a driving belt 35. The gear 32 also meshes with a gear 36 connected to the corrugating roll 28; said gear 36 being connected by an idle gear 37 with a pinion 38 on the roll 22, said pinion 38 meshing with a pinion 39 on roll 21.

As will be seen at Figure 1, the corrugations 30 on the main cylinder 31 are preferably of wavy form, and the corrugations 29 on the roll 28 correspond therewith, so that wavy corrugations 40 are formed in the superposed plies of web.

There may be also provided, at the delivery side of the main cylinder 31, a roll 41 having wavy corrugations 42 to co-operate with the cylinder 31 in pressing the corrugations into the web, and to aid in carrying the web around cylinder 31 and crush it against a crinkling and stripping doctor-blade 43, which extends down from a transverse bar or carrier 44; the paper in its crinkled condition being shown at 45 stripped from the cylinder, and passing from the machine over a delivery belt 46.

It will be understood that the corrugations in the three rolls 28, 31, 41 correspond in their undulations, so that the paper is properly corrugated with the wave-like corrugations; while the doctor-blade carrier 44 is caused to reciprocate automatically in a manner to agree with the undulatory course of the corrugations in the main cylinder 31, so that the scallops 47 in the blade follow the grooves of the cylinder. This reciprocation of the blade is effected by means of a roll 48 running in a peripheral cam 49.

formed upon a cylinder 50 fixed to the cylinder 31, and having a wavy form to correspond with the undulations of the corrugations in the main cylinder 31, so that the 5 blade is timed to move back and forth in coincidence with the corrugations as the cylinder revolves. The doctor-blade may be omitted where it is not desired to crinkle the paper.

10 While the invention as above described is adapted for corrugating and crinkling wide webs, still it will be understood that a narrow web may be likewise folded and corrugated and crinkled. Either the wide or narrow 15 web may remain in its folded condition for subsequent operation thereof to form the folded web into bags, etc. Or the corrugated or crinkled web may be slit longitudinally at its fold or folds, to make a plurality of webs, prior to being cut into sheets or otherwise utilized.

Variations may be resorted to within the scope of the invention, and portions of the improvements may be used without others.

25 Having thus described my invention, I claim:

1. The combination of means for moistening a web of paper, and a pair of rolls having corrugations to co-operate to form longitudinal flutings or corrugations in the web, the corrugations in the rolls having wave-like configuration.

2. The combination of means for moistening a web of paper, a pair of rolls having corrugations to co-operate to form longitudinal flutings or corrugations in the web, the corrugations in the rolls having wave-like configuration, and a doctor-blade against which the corrugated paper is carried to effect cross-crinkling of the web.

3. The combination of means for moistening a web of paper, a pair of rolls having corrugations to co-operate to form longitudinal flutings or corrugations in the web, the corrugations in the rolls having wave-like configuration, a doctor-blade against which the corrugated paper is carried to effect cross-crinkling of the web, said doctor-blade having scallops or projections to extend into the grooves in one of the rolls, and means for reciprocating the doctor-blade to correspond with the undulatory configuration of the corrugations in the roll.

4. The method of longitudinally corrugating a web, comprising folding the web to reduce its width, and corrugating it, while in folded form.

5. The method of corrugating and crinkling a paper web, comprising folding the web to reduce its width, corrugating it longitudinally while folded, and crinkling it while folded.

6. The method of longitudinally corrugating a web, comprising folding the web to reduce its width, then gathering it laterally

and then corrugating it, while in folded form.

7. The method of longitudinally corrugating a web, comprising folding the web to reduce its width, then gathering it laterally and then corrugating it, while in folded form, and crinkling it while folded.

8. The herein-described method, comprising wetting superposed flat webs, and corrugating them longitudinally by gripping the flat webs in a manner to slightly stretch them laterally in the operation of impressing the corrugations therein.

9. The herein-described method, comprising wetting the several plies of superposed webs, corrugating them longitudinally, and crinkling them transversely.

10. The herein-described method, comprising folding a web longitudinally, wetting the superposed plies of web, and corrugating the web longitudinally.

11. The herein-described method, comprising folding a web longitudinally, wetting the upper and lower plies, and corrugating the plies longitudinally.

12. The herein-described method, comprising folding a web longitudinally, wetting the upper and lower plies, corrugating the plies longitudinally, and crinkling them transversely.

13. The herein-described method, comprising folding over the side edges of a web to reduce its width about one-half, and corrugating the web longitudinally.

14. The herein-described method, comprising folding over the side edges of a web to reduce its width about one-half, corrugating the web longitudinally, and crinkling it transversely.

15. The herein-described method, comprising folding a web longitudinally, wetting the superposed plies of web, gathering the web laterally, and then crinkling or gathering the web longitudinally.

16. The combination with means for corrugating a web longitudinally, of means for feeding superposed plies of paper webs to said corrugating means, whereby the superposed plies are corrugated simultaneously.

17. The combination with corrugating means, of means for feeding superposed plies of paper webs to said corrugating means, whereby the superposed plies are corrugated simultaneously, and means for transversely crinkling the superposed corrugated plies simultaneously.

18. The combination with corrugating means, of means for moistening the superposed plies, and means for feeding superposed plies of paper webs to said corrugating means, whereby the superposed plies are corrugated simultaneously.

19. The combination of means for folding a web longitudinally, and means for corrugating the web longitudinally.

20. The combination of means for folding a web longitudinally, means for corrugating the web longitudinally, and means for transversely crinkling the corrugated folded web. 50
21. The combination of means for folding a web longitudinally, means for moistening the folded web, and means for corrugating the web longitudinally. 55
- 10 22. The combination of means for carrying a supply roll of paper, a former over which the web is led from the supply roll, and whereby it is folded over at its sides to reduce the width of the web, means for 60 moistening the folded web, means for corrugating the moistened web, and means for crinkling the corrugated folded web.
- 15 23. A pair of cylinders for corrugating paper, said cylinders having meshing corrugations which extend in wave-like lines 65 around the peripheries of the cylinders, and a doctor-blade to co-operate with one of said cylinders.
- 20 24. A pair of cylinders for corrugating paper, said cylinders having meshing corrugations which extend in wave-like lines 70 around the peripheries of the cylinders, a doctor-blade to co-operate with one of said cylinders, and a roll to press the paper against one of the cylinders, to aid in carrying it to the doctor-blade.
- 25 25. A pair of cylinders for corrugating paper, said cylinders having meshing corrugations which extend in wave-like lines 75 around the peripheries of the cylinders, a doctor-blade to co-operate with one of said cylinders, and a roll to press the paper against one of the cylinders, to aid in carrying it to the doctor-blade, said roll having wave-like corrugations to mesh with those in said cylinder.
- 30 26. The combination of a cylinder having corrugations which extend in wavy lines 80 around its periphery, a doctor-blade for said cylinder, said doctor-blade having tongues or scallops to project into the corrugations in the cylinder, and power-driven means to
- reciprocate the blade endwise to enable its scallops to follow the corrugations in the cylinder. 85
27. The combination of a cylinder having corrugations which extend in wavy lines around its periphery, and a doctor-blade for said cylinder, said doctor-blade having tongues or scallops to project into the corrugations in the cylinder, said blade being reciprocable endwise to follow the corrugations in the cylinder. 90
28. The combination of a cylinder having corrugations which extend in wavy lines 95 around its periphery, a doctor-blade for said cylinder, said doctor-blade having tongues or scallops to project into the corrugations in the cylinder, a cam connected to said cylinder to revolve therewith, and means connecting said blade to said cam to be reciprocated thereby. 100
29. The combination of means to moisten a web, means including a corrugated cylinder to form longitudinal corrugations in said web, the corrugations in said cylinder extending in wavy lines around its periphery, a doctor-blade to co-operate with said cylinder, said doctor-blade having scallops or tongues to extend into the grooves in the cylinder, a cam connected to said cylinder, and means connecting said blade to said cam to be reciprocated thereby as the cylinder revolves. 105
30. The combination of a device for folding a web longitudinally, means for gathering the folded web laterally, and means for transversely crinkling the gathered web. 110
- 35 31. The combination of means for folding a web longitudinally, means for moistening the web, means for gathering the folded web laterally, and means for transversely crinkling the gathered web. 115
- 40 32. The combination of means for folding a web longitudinally, means for gathering the folded web laterally, means for rolling longitudinal corrugations in the web, and means for crinkling the corrugated web. 120

WILLIAM A. LORENZ.
